(57) **CLAIM**

The ornamental design for a vehicle rain gutter, as shown and described.

DESCRIPTION

FIG. 1 is a top, right side perspective view of a vehicle rain gutter showing my new design;

FIG. 2 is a bottom, left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines illustrate symbolic break lines in the length of the vehicle rain gutter. The symbolic break lines, and any portion of the article between the break lines, forms no part of the claimed design.
